CHARLES E. SMITH, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 873,964.

Specification of Letters Patent.

Patented Dec. 17, 1907.

Application filed April 7, 1906. Serial No. 310,450.

To all whom it may concern:

Be it known that I, CHARLES E. SMITH, citizen of the United States, and resident of the borough of Brooklyn, city of New York, 5 in the county of Kings and State of New York, have invented certain new and useful Improvements in Type-Writing Machines, of which the following is a specification.

My invention relates to billing mechanism 10 for typewriting machines and more particularly mechanism for doing "condensed record" work.

One object of my invention is to provide simple and efficient billing mechanism operative to aid in mechanically positioning the platen and with the aid of which "condensed record" and other billing work can be readily done without taxing the mind of the operator with mental calculations or the recollection 20 of given indices or numerals and without taxing the eyes and mind of the operator in observing when parts are in certain positions relatively to each other.

Another object of my invention is to provide simple and efficient mechanism in the nature of an attachment which can be readily applied to existing forms of typewriting machines without changing the structural features of said machines.

30 A still further object of my invention is to provide billing mechanism for "condensed record" and other billing work in which the use of index numerals or indices may be entirely dispensed with.

35 To the above and other ends which will hereinafter appear, my invention consists in the features of construction, arrangements of parts and combinations of devices to be hereinafter described and particularly pointed out in the appended claims.

In the accompanying drawings wherein like reference characters designate corresponding parts in the various views, Figure 1 is a fragmentary end elevation, partly in section and showing the upper portion of a typewriting machine with the features of my invention applied thereto, the section being taken on the line $x-x$ of Fig. 2 and looking in the direction of the arrow at said line. 45 Fig. 2 is an enlarged detail fragmentary longitudinal sectional view showing the left-hand end of the platen and some of the co-operating billing devices, the section being taken centrally and longitudinally of the 50 platen. Fig. 3 is a fragmentary plan view of

a platen and platen frame showing the features of my invention connected therewith. Fig. 4 is an enlarged detail perspective view of one of the stop members to be hereinafter more fully described. Fig. 5 is an enlarged 60 detail fragmentary sectional view of a two-part finger wheel constructed in accordance with my invention, the section being taken centrally through the finger wheel and showing the clutch sections in the released position. Fig. 6 is a like view of the same showing the clutch members in the locked or engaging position. Fig. 7 is a view which corresponds to Fig. 5 of a modified form of clutch device embodying my invention. 70 Fig. 8 is a detail inner face view of one of the clutch members shown in Fig. 7. Fig. 9 is a detail sectional view corresponding to Fig. 2 and showing a modified form of stop mechanism. Fig. 10 is a detail side view illustrating 75 certain of the parts shown in Fig. 9, some parts being shown in section.

I have shown my invention applied to a No. 6 Remington typewriting machine to which machine my attachment may be readily 80 connected without materially changing the structural features of said machine; but it should be understood that the attachment may be applied to various styles of typewriting machines.

The top plate of the machine, diagrammatically illustrated at 1, supports upwardly projecting lugs or standards 2 on which a traverse rod 3 is mounted. A carriage truck 4 carries rollers 5 which co-operate with the traverse rod 3, and the truck supports the usual paper table 6. Links 7 pivotally connect a platen frame 8 to the truck 4 and the forward side of the platen frame carries a roller 9 which co-operates 90 with the usual shift rail 10, the latter supporting the forward side of the platen frame. A platen 11 is mounted to rotate in the platen frame and a line spacing wheel 12 is connected to the right-hand end of the 110 platen. A detent roller 13 is carried by the usual spring 14 secured to the platen frame by a screw 14a, the roller bearing against the teeth of the line spacing wheel. A line spacing pawl 15 is pivoted at 16 to an actuating lever 17 pivoted at 18 to a downwardly and forwardly extending bracket arm 19 on the platen frame. The lower arm 20 of the lever 17 serves as a handle by which the line spacing pawl may be actuated. A spring 21 co- 105 110

operates with the lever 17 to restore it to the normal position shown in Fig. 1 and to bring the tail 22 of the line spacing pawl into cooperation with one of the contact faces 23 on a controlling device 24 which is pivoted at 25 to an upwardly and forwardly extending bracket arm 26. A spring 27 co-operates with the controlling device 24 in the usual manner to retain it in any one of the three 10 different positions to which it may be set, so as to bring any one of the contact faces 23 into the path of the tail 22 of the line spacing pawl, and thus determine the extent of line spacing movement which may be transmitted 15 to the line spacing wheel and the platen which is connected therewith. A platen shaft 28 is received in the bearing at the right-hand end of the platen frame and extends therethrough, and a finger wheel 29 20 is connected to said shaft by a screw 30. A platen head 31 at the left-hand end of the platen is of essentially the usual construction and is secured by wood screws 32 to the wooden core 33 of the platen. The platen 25 head has an outwardly extending hub or boss 34, said boss being slightly shorter than that usually provided (Fig. 2). A central opening extends through the platen head and boss and through said opening passes the 30 platen shaft 28, said shaft being secured to the platen head by a screw 35 which is received in a threaded opening in the boss 34 and bears at its inner end against the shaft 28. A disk 36 is provided with a cylindrical 35 hub 37 which extends from the outer face of the platen head 31 to the inner face of the left-hand side or end bar of the platen frame 8 (Fig. 2). This hub is mounted in part on the boss 34 of the platen head 31, the construction being such as to afford a turning movement of the platen independently of the hub and the disk carried thereby. An opening 38 is formed in the hub 37 to give 40 access to the screw 35 which connects the platen head 31 to the shaft 28. A threaded opening is provided in the hub 37, on the outer side of the disk, to receive a screw 39, the inner end of said screw bearing against a sleeve 40 which extends through and turns 45 freely in a bearing opening in the platen frame. The platen shaft 28 extends through said sleeve and projects beyond the outer end thereof. The disk 36 is provided with a circular series 50 of locking openings 41 (Figs. 1 and 2) which extend transversely therethrough and are preferably equal in number to the teeth of the line spacing wheel and correspond in spacing to said teeth; thus, if the line spacing 55 wheel be provided with thirty-three teeth the disk 36 will have thirty-three openings 41 circularly arranged and the spacing between which corresponds to the spacing between the teeth of the ratchet wheel. On each 60 side of the disk 36 is mounted a stop member,

such as that shown in detail in Fig. 4. Said stop member comprises a ring-like body portion 42 which surrounds the hub 37 at one side of the disk, the opening in the ring-like member 42 having substantially the same 70 diameter as the hub. The inner edge of the opening in the ring may be beveled or rounded as indicated at 43 for purposes which will hereinafter appear. A stem-like portion or shank 44 projects from the ring 42 and carries a stop 45 at its outer end, said stop preferably projecting laterally over the periphery of the disk, as shown in Fig. 2. The stop on the member at the inner side of the disk is numbered 45 while the stop on the member 80 at the outer side of the disk is numbered 45^a. A laterally projecting pin 46 is carried by the arm 44 and is adapted to be seated in any of the openings 41 in the disk 36. 75

A coiled expansion spring 47 surrounds the 85 hub 37 and bears at one end against the platen head and at its opposite end against the ring 42 of the inner stop member so as to force the stop member outwardly towards the disk and maintain it locked in place with 90 the pin 46 seated in one of the engaging openings in the disk. A second coiled spring 48 surrounds the outer portion of the hub 37 and bears at one end against the ring-like 95 portion of the outer stop member and at its other end against a washer 49 which surrounds the hub and bears against the inner face of the left-hand end bar of the platen frame. This spring tends to force its associated stop member inwardly towards the 100 disk and to maintain the locking pin 46 seated in one of the engaging openings 41.

In order to effect an adjustment of either of the stop members on the disk it is merely necessary to press against the stop portions 105 45 or 45^a in a direction opposite to that in which pressure is applied by the associated spring. The beveled or rounded edges 43 of the ring portion will afford a slight swinging movement of the stop member against 110 the tension of its associated spring, sufficient to enable the pin 46 to be disengaged from the opening 41 in which it is seated. The stop member may then be turned around the hub and the pin 46 may be engaged in another opening 41 to secure the stop member in its newly adjusted position. By mounting the stops 45 and 45^a (together) 115 with their carrying portions on opposite sides of the disk 36 either of the stops may be adjusted on the disk relatively to the other without interference from the other stop or the member which carries it.

The sleeve 40 which, as hereinbefore explained, is received in a bearing opening in 125 the platen frame and supports the platen shaft at the left-hand end thereof is rigidly connected by the set screw 39 to the disk and the stops carried thereby. The outer free end of this sleeve has a clutch member 130

secured thereto, said clutch member being clearly shown in Figs. 2, 5 and 6. The clutch member may be in the nature of one section of a two-part finger wheel, said section 50 having a central opening or depression 51 therein. The side walls 52 of the opening are inclined and constitute an engaging or clutch face which co-operates with a conoidal portion or clutch member 53 on the other section or member 54 of the two-part finger wheel, which section 54 may in itself be regarded as a finger wheel. The section or finger wheel 54 is adapted to receive a slight movement longitudinal of the platen on a cylindrical bearing stud 55 which has a threaded stem 56 at its inner end, said stem co-operating with a tapped opening in the end of the platen shaft 28. A laterally projecting spline 57 extends from the stud 55 and is received in a groove in the finger wheel 54. The spline 57 may be driven into a longitudinally extending groove in the stud 55 and held therein by a drive fit. The construction is such that the platen shaft and finger wheel are caused to rotate together although the finger wheel is capable of a slight independent movement longitudinal of the platen.

The outer end of the bearing stud 55 is bifurcated at 58 for the reception of a cam or locking piece 59 pivoted thereto at 60 and provided with a finger piece 61 by which it may be manipulated. A recess or opening 62 is provided in the finger wheel for the reception of an expansion spring 64 which surrounds the platen shaft and bears at one end against the outer end of the sleeve 40 and at its other end against the bottom wall of the opening 62. The pressure of this spring is exerted to force the two clutch members apart, as shown in Figs. 2 and 5, when the cam or locking piece 59 is moved to the position shown in said figures. When, however, the cam piece is moved to the position shown in Fig. 6 the cam edge 65, during such movement, will cooperate with an edge 66 of the bearing opening in the finger wheel 54 to force said finger wheel to the right so that the two members 50 and 54 of the clutch will be brought into rigid clamping engagement as shown in Fig. 6. With the parts disposed as shown in said figure, the platen, the disk 36, the stops 45 and 45^a, and the two part finger wheel are all locked to rotate together.

When, however, the cam device 59 is moved to the position shown in Figs. 2 and 4 the finger wheel 54 will be moved outwardly to release the clutch members, thus effecting a disconnection between the platen and the rotary stops 45 and 45^a. At this time the finger wheel 54, or the finger wheel 29 at the other end of the platen, may be employed to turn the platen independently of the rotary stops 45 and 45^a and the disk which carries them.

A stop 67 which is in the nature of a bracket arm may be secured in place on the platen frame by any suitable means such as the screws 68 and 69. This stop is secured to the front bar of the platen frame near the left-hand end of the platen and projects rearwardly so that the free end thereof will project into the path of the rotary stops 45 and 45^a (Figs. 1 and 3).

It will be understood that when the cam piece 59 has been moved to the position illustrated in Fig. 6 to effect a locking engagement between the clutch members, the rotary stops and the platen will be locked to turn together, and the platen will be arrested in its forward or backward rotation when the stop 45^a or 45 come into contact with the fixed stop 67. That is to say, when the clutch sections are locked together, the platen will be arrested during the forward rotation thereof by the stop 45^a coming into engagement with the fixed stop 67, and further forward rotation of the platen cannot take place until the clutch members are disengaged. In a like manner the platen is arrested during its rearward rotation when the stop 45 comes in contact with the fixed stop 67, and further rearward or backward rotation cannot be effected without releasing the clutch members.

It will be seen that the movement of the finger wheel 54 into and out of clutching engagement is a movement longitudinally of the platen and may be effected while the platen is at rest and without disturbing the rotary stops and may be effected while either of the rotary stops is in contact with the fixed stop 67. It will also be seen that the cam piece 59 not only constitutes means for effecting a clutching engagement between the clutch members but that it also constitutes locking means for maintaining the clutch members locked together and for maintaining the rotary stops locked to the platen, and that the clutching means enable the platen to be positively arrested by the stop devices or to be freed from arrest by said stop devices at will.

In doing "condensed record" work, bill or invoice sheets of a given character are employed and a copy of the different items as they are typewritten on the various bills is reproduced through an interposed carbon sheet on what is termed a "condensed record", charge or sales sheet. The copy of one bill on the record sheet follows closely after the copy of the preceding bill without leaving a space on the sales sheet corresponding to the printed matter or "bill head" of the invoice sheet.

I will now describe one method of employing my devices for "condensed record" work.

It is necessary first to set the stops for the particular character of work to be done or for the particular character of invoice sheets employed. This may be accomplished as fol-

lows:—The clutch members 50 and 54 being disengaged, the disk 36 may be turned by the section 50 of the two-part finger wheel until the stop 45 is brought into engagement with the fixed stop 67, as shown in Fig. 1. A bill or invoice sheet, a "condensed record" sheet, and interposed carbon sheet, are then entered in the machine with the leading edges of said sheets together and the record sheet 10 next to the platen and with the leading edges of the sheets at the points where the feed rollers *a* contact with the platen. The clutch members are then clamped together and the platen is turned until the part of the bill or 15 invoice where the first line of writing is to appear is brought to the printing line. This is determined in the first instance by swinging the platen frame back and observing when the point or line in question reaches the 20 printing line. The forward feed movement of the platen just described is effective to carry the stop 45 away from the fixed stop 67 a distance corresponding to the extent of rotary movement that has been given to the 25 platen in feeding the invoice, carbon and record sheets forward. The part of the invoice sheet where the first line of writing is to appear having been brought to the printing line in the manner described, the stop 45^a is 30 now adjusted on the disk 36 to a position where it will contact with the under side of the fixed stop 67 and said stop 45^a is then locked to the disk. It may be assumed, that the relative adjustment between the stops 45 35 and 45^a corresponds to that shown in Fig. 1. The cam device 59 may then be moved to the position shown in Figs. 2 and 5 to release the clutch members and the operator may then proceed to write the bill or invoice and a carbon 40 copy of it will be produced on the "condensed record" sheet. During the forward rotation of the platen in writing the various items on the bill sheet, the stop 45^a will be maintained in contact with the stop 67 while 45 the platen is traveling independently of said stops. This maintenance of the stop 45^a in contact with the stop 67 is effected by the frictional contact between the hub of the disk 36 and the boss 34 on the platen head 31. 50 When the invoice sheet has been written the operator will effect a double line space movement of the platen in order to provide a double line space on the record sheet between the last line of the bill just reproduced on the 55 record sheet and the first line of the next succeeding bill to be reproduced on the record sheet through the interposed carbon sheet. The operator will then move the cam piece 59 to the position shown in Fig. 6 in order to 60 effect a clutching engagement and to lock the rotary stops 45 and 45^a to turn with the platen. Either of the finger wheels 54 or 29 may then be employed to give a reverse or 65 backward rotation to the platen until it is prevented from further movement in this

direction by the contact of the stop 45 with the fixed stop 67 as shown in Fig. 1. This reverse rotation of the platen through a pre-determined distance, controlled by the rotary stops in co-operation with the fixed stop 70 67 is sufficient to bring the platen back where a new invoice sheet may be introduced outside of the invoice sheet last written. In introducing the second invoice sheet the leading edge thereof should be brought to the 75 points of engagement between the feed rollers and the platen. The platen is then turned forwardly until the stop 45^a reaches contact with the fixed stop 67 when it will be arrested. The clutch is then disengaged and 80 the last invoice sheet introduced may be written as before, the platen at this time turning independently of the stops. When the bill has been completed a double line space movement of the platen is again effected and the clutch devices are again forced into clutching engagement and a reverse rotation of the platen is given until the stop 45 is again brought into contact with the fixed 85 stop 67, as shown in Fig. 1. A new or third 90 invoice sheet may then be introduced as before outside of the invoice sheet last written and the platen may be given a forward rotation until the stop 45^a contacts with the fixed 95 stop 67 and arrests the further movement of the platen in that direction. The clutch is then released and the operator proceeds to write the third invoice; and the carbon copy 100 thereof which is produced on the "condensed record" sheet has its first line situated two line space distances from the last written line of the next preceding record on the "condensed record" sheet. This operation may continue indefinitely after the stops 45 and 45^a have once been adjusted in the manner 105 described. After a number of invoice sheets, say three, have been introduced into the machine and written, the first written invoice sheet will, during the forward movement of the platen, be fed to a position where it will 110 be fed out of the machine, or where it may be readily removed without disturbing the other sheets. When one record sheet has been filled it may be removed from the machine together with the carbon and such written 115 invoice sheets as there may be in the machine. The clutch members being engaged and the stop 45 being in engagement with the fixed stop 67, a new record sheet, a carbon sheet and new invoice sheet may be introduced into the machine as before and the platen may be turned forwardly until the stop 45 contacts with the fixed stop 67. The 120 clutch is then released and the operator then proceeds to write as before. Instead of introducing a record sheet, carbon sheet and invoice sheet into the machine with the leading edges thereof together, as hereinbefore described, the invoice sheet may 125 be given a "lead" over the other sheets suf- 130

ficient to bring the first line of the carbon copy to be produced on the record sheet near the top or leading edge of said sheet, and thus avoid an unnecessary space at the top 5 of each record sheet.

It will be understood from the foregoing description that after the stops 45 and 45^a have been adjusted relatively to each other in the manner described they are maintained 10 in fixed relation and determine the extent of backward and forward rotation which may be given to the platen when the rotary stops are connected to turn with the platen and that during the operation of the machine in 15 writing the clutch is disconnected and the platen turns independently of the stops. The only operation involved in determining the extent of backward rotation sufficient to receive a new invoice or record sheet is to 20 turn the platen backwardly until it is arrested by the stop 45 coming into contact with the fixed stop after the clutch has been locked and the only operation involved to determine the extent of forward rotation of 25 the platen necessary to bring the first line of writing off the last introduced bill to the printing point is to turn the platen forwardly until it is arrested from further movement by the stop 45^a coming into contact with the 30 fixed stop 67. This forward and backward turning of the platen to predetermined extents, and until it is arrested by the coöperation of the stops, properly positions the sheets with reference to each other and relieves the mind of the operator from making 35 any calculations or from observing any indices and greatly facilitates the speed and accuracy with which the work can be accomplished; the stops themselves mechanically 40 determining the extent of rotation to which the platen may be moved in either direction.

In Figs. 7, 8, 9 and 10 I have shown slightly modified forms of constructions embodying my invention. In the construction 45 shown in the preceding figures a clutching engagement between the parts 50 and 54 is effected through frictional connection between said parts. In the construction shown in Figs. 7 and 8 I provide a clutch member 50^a which corresponds to the member 50 shown in the preceding figures, except that a series of circularly arranged engaging teeth 70 is provided thereon for coöperation with similarly arranged teeth 71 on the finger 55 wheel 54^a. Otherwise the parts may be constructed in essentially the same manner as that previously described. It will be understood, therefore, that the clutching engagement may be effected between the parts 60 either frictionally or by positive means for connecting the rotary stops to the platen. In either case, however, the construction affords a rigid connection which prevents a rotation of the platen when either of the 65 rotary stops is brought into coöperation

with the fixed stop on the platen frame. In Figs. 9 and 10 I have shown a modified form of disk and rotary stops. In this construction only one of the rotary stops is adjustable, the stop 45^b being formed integral with a 70 disk 36^a. The periphery of the disk in this case is provided with a series of squared teeth 72, with spaces 73 between them in which a locking flange 74 of an adjustable stop member is adapted to be seated. The 75 number of the teeth 72, or of the space between them, corresponds substantially to the number of teeth of the line spacing ratchet wheel and they are spaced apart in accordance with the spacing of the teeth of 80 the line spacing ratchet wheel. A coiled spring 75, like the spring 48, bears at one end against the ring-like portion 76 of the adjustable stop and at the other end against a washer 77 which bears against the inner 85 face of the left-hand side bar of the platen frame and said spring tends to maintain the locking flange 74 in the recess 73 in which it is seated. The locking flange projects beyond the periphery of the teeth 72, as shown 90 in Fig. 10, and constitutes a stop 78 which coöperates with a fixed stop 79 on the frame of the machine. The operation of this construction is similar to that shown in the preceding figures and further description thereof 95 is deemed unnecessary.

It will be observed that it is unnecessary to make any essential changes in the construction of the typewriting machine in order to apply my invention thereto. The 100 platen shaft 28 may be the ordinary platen shaft of the machine with a tapped opening in the end thereof for the reception of the threaded stem of the bearing stud 55. However, if desired the so-called bearing stud 55 105 and the shaft 28 may be made in one piece. A slightly enlarged bearing opening may be made in the left-hand end or side bar of the platen frame to receive the sleeve 40 and the usual sleeve such as 34 on the platen head 31 110 may be cut off for a portion of its length to accommodate the sleeve 40 and to afford a connection between the sleeve 40 and the hub of the disk 36. It will also be seen that the devices are simple in construction, cheap 115 to manufacture and are efficient in operation and not cumbersome when applied to the machine.

While I have shown and described certain means for maintaining and for effecting a 120 relative angular adjustment between the rotary stops 45 and 45^a or 45^b and 78 it should be understood that from certain aspects of my invention any suitable means may be employed for this purpose. However, I prefer to provide some means such as those shown for effecting such relative angular adjustment, so that the stops may be adjusted to different points that correspond to the spacing between the teeth of the line 130

spacing ratchet wheel, because each of the adjustable stops may then always be set at a point where it will arrest the platen, in its back or forth rotary movement, in line space 5 position or will arrest the platen at a point where the detent roller 13 is properly seated between two teeth of a line spacing wheel and not at a point where the detent roller bears on the crown of a tooth of said line 10 spacing wheel. If the platen were arrested in this last mentioned position a slight accidental displacement of the platen might be effected which would result in the improper positioning of the platen, and for this reason 15 I prefer to employ some means such as those described for effecting the positioning of the adjustable stop or stops at a point or points which will correspond to a line space position when the platen is arrested by the coöperation 20 of the stops. Furthermore, the carrier 36 (or 36^a) need not necessarily be in the form of a disk, but may be of segmental or other form, since in "condensed billing" work it seldom, if ever, occurs that an angular 25 adjustment of one of the stops 45, 45^a or 78 throughout 360° is required.

From certain aspects of my invention the locking device 59 may be dispensed with and the finger wheel 54 may be moved and held 30 in the clutching engagement by hand. I prefer to employ a locking device such as 59 since it enables both hands of the operator to be employed at all times and the same amount of care need not be exercised in rotating the platen back and forth as would be necessary if a locking device was not employed. When the locking device 59 is dispensed with it may also be found desirable 35 to dispense with the spring 64 and depend 40 on the hand of the operator to move the finger wheel longitudinally of the platen into and out of clutching engagement and to depend upon the frictional engagement between the parts to maintain the finger wheel 45 in either shifted position to which it is moved by hand.

While the devices of my invention are intended primarily for "condensed record" work they may be employed for other purposes and for other forms of billing work. It is not deemed necessary to describe the methods of procedure under the various uses to which the invention may be put but, it may be well to point out that it may be 55 employed in facilitating the writing of bills or invoices or accurately filling in partly printed blanks, and that by its aid the work sheet may be accurately and mechanically positioned in the machine to receive the 60 type impressions at the proper point or points so that uniform, neat and properly positioned work on the various bill heads or other blanks may be done.

Various changes may be made without 65 departing from my invention.

What I claim as new and desire to secure by Letters Patent, is:—

1. In a typewriting machine, the combination of a platen, a finger wheel connected to turn with and fixed against turning relatively to said platen, stop devices, a second finger wheel connected with certain of said stop devices, and means for directly connecting said finger wheels and thereby connecting the parts controlled by said finger wheels 75 to rotate together.

2. In a typewriting machine, the combination of a rotary platen, a finger wheel connected to turn with and fixed against turning relatively to said platen, stop devices, a second finger wheel connected with certain of said stop devices, means for effecting a relative adjustment between certain of said stop devices, and means for directly connecting 80 said finger wheels and thereby connecting 85 the parts controlled by said finger wheels to rotate together.

3. In a typewriting machine, the combination of a platen, stops for arresting the rotation of the platen in opposite directions, a clutch member connected with certain of said stops and adapted to remain fixed when the platen is turned, a finger wheel movable longitudinally of the platen and fixed against, 90 rotation independently of the platen, and a clutch member connected with said finger wheel and adapted to coöperate with said first mentioned clutch member to lock the finger wheel, platen and certain of said stops to rotate together.

4. In a typewriting machine, the combination of a platen, stops adapted to arrest the platen in its rotation in opposite directions, a two-part finger wheel, each part carrying a clutch member, one part of the finger wheel 100 being connected to turn with said platen and the other of said parts being connected to certain of said stops and relatively to which the first mentioned part may receive a continuous rotation.

5. In a typewriting machine, the combination of a platen, a platen shaft, stops for arresting the rotation of the platen in opposite directions, certain of said stops being adapted to rotate around the platen shaft, a clutch member operatively and fixedly connected with certain of said stops, a finger wheel that is splined to the platen shaft, and a second clutch section fixedly connected with said finger wheel and by means of which it is 110 moved into and out of clutching engagement with said first mentioned clutch section.

6. In a typewriting machine, the combination of a platen, a platen frame, a platen shaft, two relatively adjustable stops which are adapted to rotate around said platen shaft, a coöperating stop carried by the platen frame and adapted to arrest the rotation of the platen in opposite directions, a clutch member connected with said rotary 125 130

stops, a finger wheel connected to rotate with the platen and to receive an independent movement longitudinally thereof, and a clutch member rigidly connected with said finger wheel and coöperative with said first mentioned clutch member to lock the finger wheel, rotary stops and platen to turn together.

7. In a typewriting machine, the combination of a platen, a platen frame, a platen shaft, two relatively adjustable stops which are adapted to rotate around said platen shaft, a coöperating stop carried by the platen frame and adapted to arrest the rotation of the platen in opposite directions, a clutch member connected with said rotary stops, a finger wheel connected with and fixed against rotation relatively to the platen but mounted to receive an independent movement longitudinally thereof, a clutch member connected with said finger wheel and adapted to cooperate with said first mentioned clutch member to lock the finger wheel, rotary stops and platen to turn together, and a locking device for locking said clutch members in clutching engagement.

8. In a typewriting machine, the combination of a platen, a platen frame, a platen shaft, two relatively adjustable stops which are adapted to rotate around said platen shaft, a coöperating stop carried by the platen frame and adapted to arrest the rotation of the platen in opposite directions, a clutch member connected with said rotary stops, a finger wheel connected to and fixed against rotation relatively to the platen but capable of receiving an independent movement longitudinally thereof, a clutch member connected with said finger wheel and adapted to coöperate with said first mentioned clutch member to lock the finger wheel, rotary stops and platen to turn together, and a cam pivoted to said platen shaft and adapted to force said finger wheel longitudinally of the platen and to maintain the clutch members in clutching engagement.

9. In a typewriting machine, the combination of a platen, stops adapted to arrest the platen in its rotation in opposite directions, a two-part finger wheel, each part carrying a clutch member, one part of the finger wheel being connected to said platen and the other to certain of said stops, and a cam for effecting a clutching engagement between said clutch members and for locking them in clutching engagement.

10. In a typewriting machine, the combination of a platen, stops for arresting the rotation of the platen in opposite directions, a clutch member connected with certain of said stops and adapted to remain fixed when the platen is turned, a finger wheel that is movable longitudinally of the platen and is fixed to rotate with the platen, a clutch member connected with said finger wheel

and adapted to coöperate with said first mentioned clutch member to lock the finger wheel, platen and certain of said stops to rotate together, and a hand actuated device for locking the clutch members in clutching engagement.

11. In a typewriting machine, the combination of a platen, a platen frame, stops adapted to arrest the platen in its rotation in opposite directions, a disk carrying certain of said stops and certain of said stops being carried by the platen frame, and a two-part clutch, one member of the clutch being connected to said disk and the other member being connected with said platen, a finger wheel rigidly connected with said last mentioned clutch member, and a hand actuated device for locking the clutch members in clutching engagement.

12. In a typewriting machine, the combination of a platen, a platen shaft, stops for arresting the rotation of the platen in opposite directions, certain of said stops being adapted to rotate around the platen shaft, a clutch member operatively and rigidly connected with certain of said stops, a finger wheel that is splined to the platen shaft, a second clutch section connected with said finger wheel and by means of which it is moved into and out of clutching engagement with said first mentioned clutch section, and a hand actuated cam pivoted to the platen shaft and adapted to bear against said finger wheel and move it to establish a clutching engagement between the clutch members and to lock them in such engagement.

13. In a typewriting machine, the combination of a platen, stops for arresting the platen in the rotation thereof, a two-part finger wheel, a conoidal clutch member formed on one part of said finger wheel, and a co-operating clutch member formed on the other part of said finger wheel, one of the parts of said finger wheel being connected with the platen and the other with certain of said stops, said clutch members affording a continued rotation of one part of the finger wheel independently of the other or locking them to rotate together.

14. In a typewriting machine, the combination of a platen, a platen shaft, stops adapted to arrest the rotation of the platen, a sleeve loosely mounted on the platen shaft and connected with certain of said stops, and a two-part finger wheel each part having a clutch member, one of said parts being connected with the platen and the other with said sleeve.

15. In a typewriting machine, the combination of a platen, a platen shaft, stops operative to arrest the rotation of the platen, a sleeve loosely mounted on the platen shaft and connected with certain of said stops, a two-part finger wheel each part having a clutch member, one of said parts being con-

nected with the platen and the other with said sleeve, and means for locking the two parts of said finger wheel in clutching engagement.

5 16. In a typewriting machine, the combination of a platen, a platen frame, stops for arresting the platen in both the forward and backward rotation thereof, certain of said stops being operative to rotate with the 10 platen or to afford an independent rotation thereof and being situated between the platen and platen frame, and certain of said stops being carried by the platen frame, a sleeve that extends through a bearing in the 15 platen frame and connects with said rotary stop or stops, and a clutch device outside of the platen frame for operatively connecting said rotary stop or stops to rotate with the platen or to afford a rotation of the platen 20 independently thereof.

17. In a typewriting machine, the combination of a platen, a platen frame, a carrier situated between the platen and platen frame, stops carried by said carrier, a co-operating stop on the platen frame; a sleeve extending through a bearing in the platen frame and connected to said carrier, and means outside of the platen frame for operatively connecting said sleeve to the platen 30 at will.

18. In a typewriting machine, the combination of a platen, a platen frame, stops for arresting the platen in both the forward and backward rotation thereof, certain of said 35 stops being operative to rotate with the platen or to afford an independent rotation thereof and being situated between the platen and platen frame, and certain of said stops being carried by the platen frame, a 40 sleeve that extends through a bearing in the platen frame and connects with said rotary stop or stops, a finger wheel fixedly connected to turn with the platen and situated outside of the platen frame, and a clutch device 45 for fixedly connecting said sleeve to the finger wheel at will.

19. In a typewriting machine, the combination of a platen, a platen frame, a carrier situated between the platen and platen 50 frame, stops carried by said carrier, a co-operating stop on the platen frame, a sleeve extending through a bearing in the platen frame and connected to said carrier, a finger wheel fixedly connected to turn with the 55 platen and situated outside of the platen frame, and hand actuated clutching means for fixedly connecting said carrier to said finger wheel.

20. In a typewriting machine, the combination of a platen, a platen frame, a disk situated between the platen and platen frame,

stops carried by said disk, means for effecting a relative angular adjustment of the stops on said disk, a co-operating stop on the platen frame, a sleeve extending through a bearing 65 in the platen frame and fixedly connected to said disk, and means outside of the platen frame for operatively connecting said sleeve to the platen at will, whereby the disk and stops carried thereby may be connected to 70 rotate with or may be disconnected to afford an independent rotation of the platen as may be desired.

21. In a typewriting machine, the combination of a platen, a platen frame, stops for 75 arresting the platen in both the forward and backward rotation thereof, certain of said stops being operative to rotate with the platen or to afford an independent rotation thereof and being situated between the platen 80 and platen frame, and certain of said stops being carried by the platen frame, a sleeve that extends through a bearing in the platen frame and connects with said rotary stop or stops, a finger wheel connected to said sleeve, 85 a second finger wheel fixedly connected to turn with the platen, and means co-acting with said finger wheels for locking them together.

22. In a typewriting machine, the combination of a platen, a platen frame, a carrier situated between the platen and platen frame, stops carried by said carrier, a co-operating stop on the platen frame, a sleeve extending through a bearing in the platen 95 frame and connected to said carrier, a finger wheel connected to said sleeve, a second finger wheel, fixedly connected to turn with the platen, and means co-acting with said finger wheels for locking them together. 100

23. In a typewriting machine, the combination of a platen, a platen frame, a disk situated between the platen and platen frame, stops carried by said disk, means for effecting a relative angular adjustment of the stops on 105 said disk, a co-operating stop on the platen frame, a sleeve extending through a bearing in the platen frame and fixedly connected to said disk, a finger wheel fixedly connected to said sleeve, a second finger wheel fixedly connected to turn with the platen, and co-operating clutch devices formed on the finger wheels. 110

Signed at the borough of Manhattan, city of New York, in the county of New York, and 115 State of New York, this 6th day of April, A. D. 1906.

CHARLES E. SMITH.
